UNITED STATES PATENT OFFICE.

ARTHUR DICKERSON, OF SALT LAKE CITY, UTAH.

WATER-WHEEL REGULATOR.

1,279,848.

Specification of Letters Patent. Patented Sept. 24, 1918.

Application filed November 6, 1916. Serial No. 129,887.

To all whom it may concern:

Be it known that I, ARTHUR DICKERSON, a citizen of the United States, residing at Salt Lake City, in the county of Salt Lake 5 and State of Utah, have invented certain new and useful Improvements in Water-Wheel Regulators, of which the following is a specification.

My invention relates to water wheel governors and has for its object to provide a fluid operated governor for prime movers and consists of certain novel constructions and combination of parts herein described and claimed whereby it is possible to regulate 10 the source of power commensurate with the load carried by the prime mover. A further object is to regulate the flow of the water by increasing or decreasing the flow beyond the required amount in order to secure 15 the desired change quickly and then to automatically adjust the governing elements of the machine whereby the different parts may be brought into normal position commensurate with the new load carried by the 20 prime mover.

These and other objects which are apparent I accomplish with the improvement illustrated in the accompanying drawings in which similar letters and numerals of reference 25 indicate like parts throughout the several figures and as described in the specification forming a part of this application and pointed out in the appended claims.

In the drawings in which I have shown a 30 substantial embodiment of my invention, Figure 1 is a side elevation of the machine.

Fig. 2 is a front elevation of the same.

Fig. 3 is a vertical section on line 3-3 of Fig. 2.

Fig. 4 is an elevation in detail of the main hydraulic valves and stem, somewhat enlarged from the view shown in Fig. 3.

Fig. 5 is a view partially in section of the dash-pot and with parts in elevation showing 45 interior of the valve chest with the valves and valve stem removed.

Fig. 6 is a plan view of the perforated piston operated in the dash-pot.

Fig. 7 is a transverse section on line 7-7 50 of Fig. 6.

Fig. 8 is a longitudinal section of the dash-pot valve rod and stem.

Fig. 9 is a side elevation of the arm of the bell crank lever showing the roller mounted 55 thereon.

Fig. 10 is an elevation in detail of the buffer elements.

The present invention consists of a metal oil tank A, which is filled with oil not under pressure but kept moving through the valve chest B by the rotary oil pump C and the connecting pipes D and E. The flow of the oil through the valve chest B and pipes D and E operates the various governing elements of the machine, and by them the water gate is instantly and automatically regulated in proportion to the load carried by the prime mover.

The main drive shaft of the governor is the rotary pump shaft 1 which is rotated by 70 the prime mover through the pulley 2. The said shaft 1 extends through the oil tank A and is mounted in bearing that are secured on the walls of said tank. On the end portion of said shaft 1 opposite the said pulley 2 is another loosely carried pulley 3 having extended hubs 4 and 5. In the hub 4 adjacent the said oil tank A is cut a spirally disposed cam slot 6. The said slot extends only partially around the said hub and opens 80 into the bore of said hub. A square shoe 7 is carried on a radially extended pin 8 that is secured in said shaft 1, and said shoe is operated in said slot 6 whereby the pulley 85 is moved toward or from said tank A as the said shaft is rotated; the said pin moving the shoe in said slot acts as a screw to move the pulley 3. A loose coil spring 109 has one end secured to said shaft 1, by a collar 108, and the other end is fastened to the said hub 90 4, which spring will, when the device is in use, normally hold said pulley in such position that the said shoe 7 is about the medial point in said slot 6 but any deviation from the set speed of the said shaft 1 will move 95 the shoe in the slot, and thereby the position of the pulley 3 will be shifted longitudinally on the shaft 1.

The outer hub 5 of the said pulley 3 has a collar flange 9 formed thereon and a roller 14 mounted on the depending arm 10 of a bell crank lever 11 contacts with said collar flange 9. The said bell crank lever 11 is pivoted on an extended bracket 12 that is secured to said tank A. The weight of the 100 bell crank lever 11 keeps a roller 14 that is mounted in the end of the arm 10 in contact with said collar flange 9. The said pulley 3 is belt connected to the fly ball frame G by the belt 16. The fly ball frame 110

G consists of a small pulley 21, over which the belt 16 is operated, the horizontally disposed flat springs 15, the fly-balls 22, and the sleeve 23 on which the disk 18 is fastened. The fly ball frame G is loosely carried on a shaft 20 which is mounted in the heart shaped rack 17 which is fastened to the side of the valve chest B. An annular disk 18 is mounted on and rotates with said fly-ball frame G. A buffer element H is mounted on said rack 17 and consists of a bearing standard 24 having an internally threaded sleeve 25 on its upper end. A buffer bolt 26 is threaded to operate in said sleeve 25 and is provided with a recessed buffer head 27 which head carries a leather washer that is adapted to bear against the said disk 18. A friction lever 28 is carried on said bolt 26, and the upper end of link rod 30 is pivoted through one end portion of said friction lever 28. The outer end of said buffer bolt 26 is squared to provide a wrench engaging portion for adjusting. The buffer bolt 26 is threaded and may be longitudinally moved by said threads by two methods. First, said bolt may be rotated and thus moved longitudinally by manually using a wrench on its squared head, this is done for adjustment. Second, it may be partially rotated by moving the friction lever 28, which lever is held in gripping contact around said bolt 26, and when said lever 28 is moved by the link rod 30, the bolt will be moved longitudinally. A bearing case 31 is fastened on the upper side of said oil tank A and one portion of said case is given a cylindrical form as at 32 and provided with a detachable head 33. Through the cylindrical portion of said casing a shaft 34 is operated, and within said bearing case 31 and on said shaft 34 a gear wheel 35 is fastened. The teeth of said gear wheel 35 mesh with the teeth of a rack bar 36, that is attached to the bottom of the piston rod 37 by means of which connection is made to the piston 38. The said piston 38 is operated within a cylinder 39 which is mounted on the upper end of said casing 31. Ingress and egress openings are provided in the walls of said cylinder 39, one above and the other below said piston 38, leading to the interior of said valve chest B. Oil is pumped in a continuous flow from the said oil tank A through the pipes D, valve chest B, and filling the cylinder 39 on both sides of its piston 38 is returned to the interior of said oil tank through the pipe E. The said oil enters said valve chest B through the pipe D near its medial portion. The valve chest B consists of two opposed walls 40 and 41 which are held together by the bolts 42. The inner face of each of said walls 40 and 41 are recessed to form a valve chamber 43, which is narrowed near each end to form valve seats 44 and 45 in one portion

and 46 and 47 in the other portion. Oil passages open from the interior of said valve chamber between the valve seats 44 and 45 and between the valve seats 46 and 47 to the interior of said cylinder 39, the one between 44 and 45 is shown as 48, and that between 46 and 47 is shown at 49. The valves 50 and 51, and 52 and 53 which are secured on the valve stem 54 that is pivoted to the middle of a floating lever 80. The said floating lever 80 is medially pivoted to the lower end of the valve stem 54, and has one end operatively connected with the dash-pot cylinder 60, and the other end connected with the link rods 30 and 81. The link rods 30 connects with the buffer elements and the link rod 81 with one end of the bell-crank lever 11. The said floating lever 80 is the connecting means whereby the fly-balls, the buffer element, the pulley 3 and its connections and the dash-pot and its connections are operatively brought together and through which they co-act to produce the governing features of the present invention. On the upper end of said valve stem 54, a locking collar 55 is secured, against which collar a set screw 56 may be manually set to lock the valve stem 54 as desired. A threaded bearing 57 is fastened on the upper end of said valve chest B within which said set screw is operated.

A vertically disposed oil filled dash-pot member K is suspended at the side of said valve chest B by means of an eye bracket 65. Said bracket extends from the cylinder base 100 to which it is secured and is formed as a ring through which the dash-pot guides. The ring also serves the purpose of an abutment for the springs 66, one of which is above and the other below said ring 105 and are coiled around the outside of the dash-pot. These with other abutments which retain the springs form the suspension for said dash-pot. These springs are herein called compensator springs, and are 110 made equal. The said dash-pot consists of a cylindrical casing 50 which is closed at both ends and has a perforated piston 61 which is operated therein. A valve rod 62 is operated within said casing 60 and the upper 115 portion is centrally bored to provide a valve seat therein for a needle valve 63, and has two radial ports 63' opening on the opposite sides of the piston 61. The said valve 63 is formed on the lower end of the valve stem 120 64. A portion of which is threaded as at 65 to mesh with internal threads cut in the bore of said valve rod 62 and by means of which said needle valve 63 is adjusted. The lower end of said valve rod 62 is screwed into a 125 small rack bar 76 which meshes with a pinion 77 on the said power shaft 34. The said rack bar 76 is operated on the opposite side of said shaft 34 and moves opposite to the piston rod 37 on the piston 38.

Two valves 68 are arranged in the said dash-pot cylinder 60 and are yieldingly held by the spiral springs 67. The said valves 68 are normally closed and are only called 5 into action when a longitudinal movement of the cylinder 60 is great enough to compress either of the outside springs 66 to near its limit of compression at which time the required inside spring 69 will move one of 10 said valves 68, which will open the ports of that side permitting less resistance of the piston as it moves through the oil medium with which the dash-pot is filled.

The operation of my machine is as follows: 15 With power applied through the pulley 2 and shaft 1, rack, pinion and other connections the oil is pumped in a continuous flow through valve chest B and fills the cylinder 39 and all interior spaces, passing out of the 20 exhaust side of the valve chest B into a pipe E that conducts the oil back to the tank A. The two admission valves 50 and 52, and the two exhaust valves 51 and 53 are so constructed in the chest B that there must always be the equal of one valve opening, both 25 in and out, permitting a constant flow of oil.

The diversion of this oil or its pressure is made to either end of the cylinder 39 by the valve movements, for the valves in a central 30 position will give equal pressure in each end of the cylinder 39 at rest, and should any change from this central position be made the force will be instantly diverted without loss of time to the required side of the piston 35 38. As the oil is not under air pressure there will be no carbonizing, and as the oil is in constant movement it will keep warm.

In the present invention the hydraulic power of the moving oil is a continuous 40 force rigidly connecting the continuous pump and the water gate or other source of power without lost motion or delay, and always gives positive action. The governing application or feature of this hydraulic 45 power, while comparatively simple in construction is somewhat difficult to describe owing to its combined and co-acting elements being so tied together in action that separate or individual action cannot be considered. The governing features must be 50 separately explained and the whole considered as a system of balances, which may be set at fixed limits, and which are disturbed by changes in the prime mover and tend to 55 quickly restore their equilibrium, or normal action which action varies and is determined by the set speed of the governor.

The main drive shaft of the governor which is also the rotary pump shaft extends 60 through the base of the machine, one end carries the pulley 2 which is operatively connected to the prime mover, and the other end of the shaft carries the loose pulley 3.

When the said pulley 3 is turned upon 65 the shaft or the shaft turned through the

pulley the action must and does move the pulley along the shaft, having the effect of a screw. This construction is a vital point, as it permits momentary differences in the speed of the shaft and the pulley to the extent of the 70

length of the slot, and in order to make a sensitive use of this difference the loose coil spring 109 is wound around the shaft 1 and one end of the spring is fixed to the pulley hub and the other end to the collar 108 75

which is made fast to the shaft by a set screw. Sufficient tension is given the spring 109, that when the pulley is turned by hand on the shaft to the limit of one end of the slot 6, the spring tension is ample to draw 80

the pulley back to the other slot limit while belted to the fly balls above and moving them also. On the other, or outer hub of the pulley 3 is the collar flange 9 which contacts with one end of the bell crank lever 11, 85

the other end of the bell crank lever is connected to another element that moves the valves to control the hydraulic power in the cylinder 39. The weight of the bell crank lever and its attachments keeps the roller 14 90

on its end in contact with the collar 9 of the loose pulley, and the longitudinal movement of the loose pulley either way moves the bell crank lever 11. The loose pulley is belt connected to the fly balls and runs them; in 95

practice the coil spring 109 on the hub of the loose pulley has sufficient tension to run the fly ball and disk and keep the loose pulley mid way between the ends of the slot 6—that is, midway between the two ends of the 100

slot so that the pulley is free to move either way when the relation of the shaft and pulley is momentarily different. This medial position of the loose pulley with regard to the limits of the slot is called the central or 105

neutral position and is normal position when the governor is set for a given speed. As previously stated, the loose pulley drives the fly-balls and the fly-balls and disk by their 110

inertia react upon the pulley. The fly-balls and disk, called the control, is fixed to its shaft 20 at the small pulley end but is free on the shaft at the disk end, so that the pull of the fly-balls outward from center draws 115

the disk end toward the opposite fixed end, this movement of the disk 18 is limited by what is called the buffer element H. As 120

previously stated, one end of the bolt 26 is recessed to receive a leather washer which contacts the side surface of the disk, a squared end of the bolt can be turned by a wrench to set the speed desired. The friction lever 28 which extends from the buffer 125

at right angles, has attached thereto a link rod that connects with other elements which tend to move it under certain conditions and also to restore it to the set speed when a speed correction has been made; this speed adjustment on the buffer is in part effected by the action of the loose pulley, and is 130

finally made by the compensator springs 66 through the floating lever connection. In this way the loose pulley arrangement and the buffer elements, by means of their belt connection and acting together, have the function of maintaining a desired speed. The normally driven speed of the pump or main shaft, being predetermined at about 450 R. P. M. will give the fly-balls about 5 1500 R. P. M. sufficient to create a proper inertia of these parts. And through the buffer, as a limiting device, to control the orbit of the fly-balls and act as a resistance or brake. Under such operating conditions 10 these parts modified somewhat by other connections, are set to run at a given speed, the normally applied power being sufficient to overcome the inertia of the moving parts and connections, also the set resistance of 15 the buffer which is acting at all times as a brake to the fly-ball limit of the centrifugal orbit. Hence if the buffer-brake be applied with more force than the fly ball orbit is reduced and the brake effect reduces the speed 20 of the moving parts, or if the buffer brake be in part withdrawn, the fly-ball orbit is increased, the brake resistance lessened and the speed of the parts increased. The centrifugal force of the fly-balls being the opposing force to the buffer elements. It 25 should be noted, that the leather faced buffer does not make a wearing contact with the surface of the disk, as a thin layer of highly compressed air is between the two surfaces under normal which are high speed 30 conditions. Thus the combination just described of loose pulley, fly-balls and buffer are co-acting elements under the control of the operator to be set with fixed limits to 35 automatically move the valves which control the hydraulic power in the cylinder. Any change in the speed of the prime mover at once changes the speed relation of the main shaft of the governor with the loose 40 pulley 3 as described, which pulley, maintains its normal set speed, therefore a slight speed difference of the prime mover will cause a movement of the pulley along the shaft either way, which by its connections 45 moves the valves and cause the hydraulic power to move the water gate of the prime mover and restore the balance between the power and load. This is done instantly and with precision, as there is an exact me- 50 chanical connection which causes a proportionate water gate movement for every horizontal movement of the loose pulley. The required movements of the different parts are very small, like the short end of a very 55 long lever, to cause a large effect on the water gate. For instance, the main valves in control of the hydraulic power, have a total movement, in a 2000 foot pounds governor, of $5/64$ of an inch, normally the 60 valves stand in the center, so that the move- 65

ment is half of this to close a full open gate sufficient to cover the throwing on or off of a full load, on the prime mover.

The loose pulley 3 is given excess movement limits to aid in positive action, but its 70 action is combined with the dash-pot elements and they jointly effect the hydraulic valves in said cylinder 39 and all three coact through the buffer elements and the rod attached to the floating lever. And this combined action through the valve rod 62, rack 75 76 and pinion 77 on the end of floating lever is the tie to the hydraulic power shaft and is sufficient to act as a neutralizer. That is to bring the hydraulic valves 50 to 53 inclusive 80 to center at the end of each piston movement. The action of the dash-pot is as follows:

The outside coil springs 66 which balance at normal speed act upon the hydraulic valves 50 to 53 through the floating lever if 85 the speed is changed. These springs 66 are brought into action by the movement of the cylinder 60. A slow movement of the perforated piston 61 will by-pass the oil through the holes 63' in the rod 62 and gives little, if 90 any, effect on the outside springs 66. While a quick movement of the said piston is resisted by the oil and moves the cylinder 60 bodily, opposed by one of the outside springs 66, and if the movement is continued, finally 95 by one of the inside springs 69, which opens one of the valves 68, in the piston and relieves the compression on the outside coil spring. The function of the dash-pot is to provide 100 an automatic element which is called into action to meet over-thrust or over-travel of power when the governor is called to add power; in effect taking the added power off in proportion to its force and absorbing the shock of change. Also the reverse effect of 105 over-balance of load as against the power called for, which the governor can only supply on condition that the water and its movement is ample to meet the load need when the gates are opened. To absorb the force 110 of an excess movement and take on or throw off power quickly and then to give up that force in a gradual correction of the disturbed normal speed, acting to oppose radical movements.

This is the general function, there are finer modifications that make for perfection of speed control under various conditions that will not in practice be generally applied, giving the governor a wide range.

To illustrate the movements in a given action, first picture the governor running at a normal set speed. The tension of the drive spring 109 is holding the pulley midway the spiral slot 6, the loose pulley and the main 125 shaft move at the same speed, the outside springs on the dash-pot are balanced, the floating lever is practically horizontal, the hydraulic valves are all away from their respective seats or in neutral position, the 130

piston in the cylinder is balanced and stationary, the buffer is applied to balance the fly-balls at the required speed; in effect the governor is idle but ready. Assume a decrease load; which has the effect to increase the speed of the prime mover, likewise the main shaft of the governor to which it is belted, the loose pulley for the time remains at the set speed, as the spring 109 yields 10 easily, two speeds are set up between the shaft and pulley, exactly measured in the travel of the pulley along the shaft outward, which, through the bell crank lever 11 and its connections to the valves, admits 15 pressure to the piston to move the gates, to reduce the power, there is no waiting, the governor action starts at the beginning and continues with a series of movements until the balance of speeds has been made. The 20 detail of the movements are described as follows:

The accelerated speed of the shaft moves the loose pulley 8 outward along the shaft, the collar 9 of the loose pulley permits the 25 lower arm of the bell crank lever to follow it outward, thus moving the opposite end of the lever downward and with it the rod connected with the center of the floating lever and drawing down the valves in the valve 30 chest B. There are four valves cut on one stem from a bar of steel, when one moves all move; beginning at the top, the first valve, the upper exhaust 50, is closed by the downward movement, the next valve, admission 35 51, is opened, the next valve, admission 52, is closed, the next, the lower exhaust 53, is opened; with the result of admitting pressure above the piston 38 which moves downward, the piston rod 37 and rack-bar 36, rotating the pinion wheel 35 thereby revolving the power shaft 34, which by another rack and pinion moves the water gate, or, other source of power, to reduce it to balance the decreased load.

45 Returning to observe other effects on the floating lever 80 which was pulled downward by the bell crank lever 11, which lever 80 as thus used has one end attached to the dash-pot as a fulcrum. The movement of 50 the power shaft in the direction to close the gate, moves the dash-pot rack 76 and rod 62 upward which compresses the lower outside spring 66 of the dash-pot in proportion to the amount and suddenness of the load 55 change, opposing the excess effect of the loose pulley to take off too much power, and returns the buffer element to its set speed which has been momentarily disturbed; the speed of the fly-balls having been momentarily 60 allowed to increase to put them in synchronous movement with the change in the prime mover to avoid the shock of too great differences effecting the power plant (not the governor), which momentary action of the fly-balls is quickly and accu-

rately restored to normal set speed by the longitudinal movement of the pulley 3. The cut out is applied to the valve stem 54 of the hydraulic valves at the very top part of the governor. An adjustable thumb screw 70 56 is tapered to a point to fit a V shaped groove in the collar 55 and thereby to move the rod 54 and bring the valves to a central position. When the cut out is applied the governor is operated by a hand wheel 70 75 geared to move the power shaft and thereby to move the water gate without shutting down the running parts of the governor.

The hand wheel 70 is used to start the governor when the plant is shut down. 80 There is no need to have the governor shut down the power plant, as this is usually objected to. The drive belt is made safe, but should it break the speed will not change until a load change occurs and hand control 85 can be had at once.

Having thus described my invention I desire to secure by Letters Patent and claim:

1. A water wheel regulator, comprising a casing; a shaft journaled thereon and connected with the controlling mechanism of the gate when said shaft is rotated; a cylinder mounted on said casing having an inlet and an outlet opening thereto; a piston operable in said cylinder having a connection 90 with said shaft whereby said shaft is rotated when said piston is moved in said cylinder; a valve chest having openings therein in communication with the openings in said cylinder; a pump driven by the prime mover and connected by pipes with the interior of said valve chest, whereby oil is continuously pumped through said valve chest; valves operable in said valve chest to direct the flow of said oil; a valve rod on which 100 said valves are formed; a floating lever medially pivoted on the lower end of said valve rod; a dash-pot carried on one end of said lever; and braking elements carried on the other end of said lever, and each adapted to 105 be moved independently and jointly by the movement of said lever; and a rack adapted to be moved by said dash-pot in opposite direction to the movement of said piston.

2. A water wheel regulator comprising 115 an oil tank; a valve chest above said oil tank; pipes connecting said tank and said valve chest; a pump to move oil contained in said tank through said pipes and said valve chest; a cylinder connected with said valve chest; a piston operable in said cylinder; a power shaft journaled below said cylinder and connected with the water gate; a gear wheel secured on said shaft and moved by said piston; a valve rod and 120 valves to direct the flow of oil through said valve chest; a floating lever medially pivoted to said valve rod; a pinion on said power shaft; a rack connected to one end of said floating lever and engaging said pinion 125 130

which is moved when said power shaft is partially rotated and when the end of said floating lever is moved; and means to dampen the movement of said floating lever.

5 3. A water wheel regulator comprising an oil tank; a valve chest above said oil tank; pipes connecting said tank and said valve chest; a pump to move oil contained in said tank through said pipes and said valve chest; a cylinder connected with said valve chest; a piston operable in said cylinder; a power shaft journaled below said cylinder; and connected with the water gate; a gear wheel secured on said shaft and moved by 10 said piston; a valve rod and valves to direct the flow of oil through said valve chest; a floating lever medially pivoted to said valve rod; a pinion on said power shaft; a rack connected to one end of said floating lever 15 and engaging said pinion which is moved when said power shaft is partially rotated and when the end of said floating lever is moved; and means to dampen the movement of said floating lever; said means consisting 20 of a dash-pot on one end and braking elements connected to the other end of said floating lever.

4. A water wheel regulator comprising a shaft connected with the water gate; a valve 30 chest; a valve rod and valves thereon operable in said chest; a cylinder having oil passages open between it and said valve chest; a piston operable in said cylinder; means operatively connecting said piston and said 35 shaft whereby the shaft is rotated when the piston is moved; a shaft connected with and rotated by the prime mover; a pulley carried on and yieldingly connected with the last mentioned shaft; a bell crank lever movable with said pulley; a floating lever adapted to fulcrum at three points and suspended from the end of said valve rod; a link rod connecting one arm of said bell crank lever at one end of said floating lever;

a buffer element to retard the movement of 45 the same end of said floating lever; and a dash pot to retard the movement of the other end of said lever.

5. A water wheel regulator comprising an oil tank; a valve chest above said oil tank; 50 pipes connecting said tank and said valve chest; a pump to move oil contained in said tank through said pipes and said valve chest; a cylinder connected with said valve chest; a piston operable in said cylinder; a 55 power shaft journaled below said cylinder and connected with the water gate; a gear wheel secured on said shaft and moved by said piston; a valve rod and valves to direct the flow of oil through said valve chest; 60 a floating lever medially pivoted to said valve rod; a pinion on said power shaft; a rack connected to one end of said floating lever and engaging said pinion whereby said power shaft is partially rotated when the 65 end of said floating lever is moved; and means to dampen the movement of said floating lever; said means consisting of a cylinder mounted between encircling springs 70 thereon which springs allow a limited longitudinal movement of said cylinder; a perforated piston operable in said cylinder; a hollow valve rod mounted longitudinally in said cylinder and on which said perforated piston is fastened and having ports opening 75 from said hollowed interior; a valve stem operable in said hollow valve rod to regulate the flow of liquid through said ports; valves carried on said hollow valve rod adapted to cover the perforations in 80 said piston; and springs carried on said valve rod to normally hold said valves against said perforated piston.

In testimony whereof I have affixed my signature in presence of a witness.

ARTHUR DICKERSON.
